UNITED STATES PATENT OFFICE.

ALFRED CHURCHER, JR., OF LYONS, ILLINOIS; EMMA M. CHURCHER CONSERVATRIX OF SAID
ALFRED CHURCHER, JR., AN INSANE PERSON.

AUTOMATIC CAR-COUPING.

No. 894,814.

Specification of Letters Patent.

Patented Aug. 4, 1908.

Application filed March 8, 1907. Serial No. 361,414.

To all whom it may concern:

Be it known that I, ALFRED CHURCHER, Jr., a citizen of the United States, residing at Lyons, in the county of Cook and State of Illinois, have invented certain new and useful Improvements in an Automatic Car-Coupler, of which the following is a specification.

This invention relates to improvements in that class of car-couplers, in which the operation of coupling is automatically performed, and it consists in certain peculiarities of the construction, novel arrangement, and operation of the various parts thereof, as will be hereinafter more fully set forth and specifically claimed.

The main object of the invention is to provide an improvement in the opening in the coupler head, and in the means for the locking and the setting of the coupling pin, and also an improvement in the fastening of the lever to the car used to raise the pin that unlocks the coupler, and, further, an improvement in the fastening of the draft rigging to the draw bar.

Various other objects and advantages of the invention will be disclosed in the subjoined description and explanation.

Referring to the accompanying drawings—
30 Figure 1 is a front view in elevation of a portion of a car, showing a coupler embodying the invention and an operating rod for the coupling pin of the coupler mounted thereon, and showing the position the parts will occupy when the knuckle of the coupler is locked. Fig. 2 is a detached perspective view of the operating rod, its supporting brackets and links, which connect said rod to the coupling pin. Fig. 3 is a longitudinal vertical view partly in section and partly in elevation, showing the position the lower part of the coupling pin will occupy with respect to the knuckle when the parts are in position to permit the cars to be detached from one another. Fig. 4 is a detail view of the pivot or bolt used for securing the knuckle in place on the coupler head. Fig. 5 is a top plan view of the coupler, showing the knuckle and coupling pin in their locked positions, and illustrating the shank of the coupler-head broken for the convenience of illustration. Fig. 6 is a vertical sectional view taken on line 6—6 of Fig. 10 looking in the direction indicated by the arrows, and showing a portion of the operating lever which

co-acts with the knuckle and coupling pin, and the housing for the upper portion of said lever. Fig. 7 is a longitudinal sectional view partly in elevation taken on line 7—7 of Fig. 5 looking in the direction indicated by the arrows. Fig. 8 is a horizontal section taken on line 8—8 of Fig. 7. Fig. 9 is a detached perspective view of the bell-crank or operating lever. Fig. 10 is a transverse sectional view through the coupler-head and coupling pin, showing the latter in its lowered position and the position the operating lever will occupy when the knuckle is locked by the coupling pin. Fig. 11 is a detached perspective view of the knuckle. Fig. 12 is a horizontal sectional view of the coupler-head and knuckle with the coupling pin removed, and illustrating the position the knuckle will occupy when ready for coupling. Fig. 13 is a transverse sectional view through the coupler-head and coupling pin, showing the latter in its raised position and illustrating the position the operating lever will occupy when the coupling pin is raised. Fig. 14 is a longitudinal vertical sectional view of a portion of the coupler-head, showing the knuckle and coupling pin in elevation and illustrating their positions when ready for the coupling operation; and Fig. 15 is a detached perspective view of the coupling pin.

Corresponding letters of reference, refer to like parts throughout the different views of the drawings.

The reference letter L designates the coupler-head, which is hollow and has a hollow shank L¹, the upper and lower surfaces of which are each provided with a countersunk groove l to receive extensions l¹ on the bar l² of the draft rigging, which may be supported on the bottom of the car, in the ordinary or any well known way, but usually spring pressed. The front end of the coupler-head L is provided near one of its walls with forwardly and horizontally extended projections m, which are spaced apart, as is clearly shown in Fig. 7, and have located between them the rearwardly extending arm or portion B¹ of the knuckle B², which is provided near its juncture with the arm B¹ with a vertical opening b to receive the pivot pin or bolt K¹, which is passed through suitable openings in the projections m to pivotally secure the knuckle in position therebetween. The bolt or pin K¹ is provided in its lower portion with a diagonally disposed opening

k, which is divided by means of an apertured partition *k*¹ to receive a pin *K*, which has on each of its ends a rounded head. The partition *k*¹ in the opening *k* of the bolt *K*¹ is located at such a position in said opening that the head on the lower end of the pin *K* will normally project therefrom, as shown in Fig. 4, which will prevent the bolt *K*¹ rising or working out of its bearings. As the pin *K* is loosely confined in the opening *k*, it is apparent that when the lower end of the bolt *K*¹ is inserted in the openings therefor, the pin *K* will be pushed up in the openings *k* so as to allow the bolt *K*¹ to pass through its openings. As is clearly shown in the drawings, the arm *B*¹ of the knuckle *B*² extends rearwardly from the knuckle, and is adapted to move between the projections *m* into and out of the cavity of the coupler-head through an opening *m*¹ in the front end thereof. The rear portion of the arm *B*¹ is provided with a vertical flange *b*¹, and the lower rear portion of said arm is provided with a horizontally disposed flange *c*, upon which latter a portion of the coupling pin is adapted to rest, as will be presently explained. The upper and lower surfaces of the arm *B*¹ are provided with lugs *B* to strike against the walls of recesses *b*² in the projections *m*, so as to prevent the knuckle turning too far towards the wall *J*² of the coupler-head nearest which it is pivoted.

As will be seen and understood by reference to Figs. 5, 6, 10, and 13 of the drawings, the coupler-head *L* is provided on its upper surface with a housing *C*, for the protection and operation of the bell-crank or operating lever, which co-acts with the coupling pin and arm *B*¹ of the knuckle to throw the latter outwardly into coupling position. The housing *C* is preferably made integral with the head *L*, and is divided therefrom by means of a horizontal partition *F*, which has an opening therein for the operation of the arm *E* of the operating lever. This lever is fulcrumed on a pin *N* secured in the walls of the housing *C*, which housing is provided on its upper surface with a hollow raised portion *C*¹ for the operation of the upper end of the operating lever when the coupling pin is raised to its upward limit. Located transversely in the walls of the raised portion *C*¹ is a pin *P*, which restricts the upward movement of the operating lever. As is clearly shown in Fig. 9 of the drawings, the operating lever is of the bell-crank type—that is—it consists of an upper portion or longer arm *D* and a shorter arm *E*, having at its lower portion another arm *E*¹ which extends laterally from the arm *E* and forwardly within the coupler-head to impinge against the vertical flange *b*¹ on the arm *B*¹ of the knuckle. When in place between the walls of the housing *C*, the arms *D* and *E* of the operating lever will move in the same plane when actuated by

the coupling pin, but the arm *E*¹ of said lever will project forwardly to move the knuckle arm, as above stated. The coupler-head is provided on its upper surface about midway between its sides with a hollow extension, which is open at its upper end and communicates at one of its sides with the cavity of the housing *C*, and consists of the front and rear walls *G* and side wall *J* (see Figs. 7, 10 and 13). The lower portion of the coupler-head is provided directly below the hollow extension above described with an opening *d*, which registers with an opening *d*¹ in the partition *F*, as well as with the opening in the hollow extension above referred to. Extending downwardly from the lower surface of the coupler-head and around the opening *d* therein is a hollow extension, which consists of the end walls *G*¹ and side walls *J*¹ (see Figs. 7, 10, 12 and 13). The front part of the opening *d* in the bottom of the coupler-head is provided with a horizontally disposed shelf or ledge *d*² on which a shoulder *a* on the coupling pin will rest when the same is in its lowered position, so as to lock the knuckle, as is clearly shown in Fig. 7 of the drawings.

By referring to Fig. 15 of the drawings, it will be seen that the coupling pin *A* is rectangular in cross-section, and has a longitudinal or vertical slot *a*¹ in which the upper end of the arm *D* of the operating lever extends and is adapted to operate. The upper end of the pin or portion *A* is provided with a head *A*¹ which is formed with a vertical opening *a*² in which is held, by means of a transverse pin *o*, a link *a*³ used for connecting the coupling pin to the operating rod on the body of the car.

The head *A*¹, which is adapted to rest, when the coupling pin is in its lowered position, on the top of the hollow extension formed by the walls or portions *G* and *J*, has on its side adjacent to the hollow raised portion *C*¹ of the housing *C* a vertical plate or portion *H*, which is designed to close said raised portion. The lower end of the coupling pin *A* is reduced to form a tenon *a*⁴, on which is pivotally secured a block *A*², which has a mortise or groove *a*⁵ in which the tenon *a*⁴ fits. As shown by dotted lines in Figs. 3 and 7, the tenon *a*⁴ has at its front lower portion a downward projection *a*⁶ which engages a shoulder *a*⁷ in the bottom of the mortise *a*⁵ of the block *A*², so as to restrict the movement of the block when it engages the flange *c* on the arm *B*¹ of the knuckle, as will be understood by reference to Fig. 3 of the drawings. The coupling pin *A* is formed or provided on its front portion with a longitudinally extending rib *A*⁸, which extends from the head *A*¹ to near the lower end of the pin *A*, but terminates above the block *A*², thus forming a shoulder *a*, which will rest on the ledge or shelf *d*² when the coupling is in its lowered position, as shown in Fig. 7.

Secured transversely and horizontally on the end of the car R, by means of brackets r, at a suitable distance above the coupler, is an operating rod S, which has at one of its ends a crank s to turn the same, and at its other end an arm s¹ to which the link or links a³ on the coupling pin is attached. That portion of the rod S on which the arm s¹ is formed is located in a slot M formed in a link M¹ which is pivoted at its other end to one of the brackets r. By this arrangement, it is apparent that the coupling pin may be readily raised to the desired position, and that the link M¹ will permit of sufficient movement of the rod S to correspond with the movement of the coupler-head, and thus avoid the use of long chains which might interfere with the operation of the coupling pin.

The operation of the device is simple and as follows—In the locked or coupled condition, the parts will assume the positions shown in Figs. 5, 7 and 10—that is to say—the coupling pin A will be located in its lower-most position when its head A¹ and its shoulder a will rest on the upper ends of the walls G and J and on the ledge d², respectively, in which positions the coupling pin will firmly hold the arm B¹ of the knuckle against outward movement, for it is apparent that the free end of the arm B¹ will rest against the surface of the coupling pin adjacent to the pivot of said arm. When it is desired to uncouple or to permit the cars to be detached, the coupling pin may be partially raised by means of the operating rod S, or otherwise, when by reason of its upward movement and the movement of the operating lever, the arm B¹ and knuckle B² will be turned slightly outward when the block A², which is eccentrically pivoted on the coupling pin, will engage and rest on the ledge or flange c of the arm B¹, as shown in Fig. 3, thus supporting the coupling pin in its partially raised position, when, as soon as draft is applied to the knuckle, it will turn outwardly, thus permitting the block A² to engage or rest on the ledge d² and the coupling pin to be correspondingly lowered, as is shown in Fig. 14. When in this last-named position, the coupling operation may be performed by applying rearward pressure to the arm B¹ of the knuckle, which, in its movement, will force the block A² off the ledge d², and by means of the flange b¹ on said arm, will move the arm E¹ of the operating lever from the coupling pin, thus permitting the latter to assume its lowermost or locked position.

Having thus fully described the invention, what I claim as new, and desire to secure by Letters-Patent, is—

1. In an automatic coupler, the combination with a hollow coupler-head having openings in its top and bottom for the reception and operation of the coupling-pin and provided at the front part of the lower opening

with a ledge, of a knuckle pivotally supported on the head and having an arm adapted to extend into the cavity of the same, a longitudinally slotted coupling-pin movably located in the openings of the coupler-head 70 and having at its upper end a head and near its lower end a shoulder adapted to rest on said ledge, the said pin having at its lower end a reduced portion provided with a downwardly extending projection, a block having 75 a shouldered mortise to receive and engage the reduced portion of the coupling-pin and projection thereon, respectively, and pivotally secured to said reduced portion, a bell-crank-operating-lever fulcrumed on the 80 coupler head and having one of its arms extended into the slot of the coupling-pin and another of its arms projected forwardly to co-act with the arm of the knuckle, substantially as described.

2. In an automatic coupler, the combination with a hollow coupler-head having on its upper portion a housing and provided in its top and bottom with openings for the reception and operation of a coupling-pin and provided at the front part of the lower opening with a ledge, of a knuckle pivotally supported on the head and having an arm adapted to extend into and traverse the cavity of the same, a horizontally disposed flange on the 95 lower portion of said arm, a longitudinally slotted coupling-pin movably located in the openings of the coupler-head and having at its upper end a head and near its lower end a shoulder adapted to rest on said ledge, the 100 said pin having at its lower end a reduced portion provided with a downwardly extending projection, a block having a shouldered mortise to receive and engage the reduced portion of the coupling-pin and projection 105 thereon, respectively, and pivotally secured to said reduced portion, a bell-crank-operating-lever fulcrumed in the said housing on the coupler-head and having one of its arms extended into the slot of the coupling-pin 110 and another of its arms projected forwardly to co-act with the arm of the knuckle, substantially as described.

3. In an automatic coupler, the combination with a hollow coupler-head having on its upper portion a housing and provided in its top and bottom with openings for the reception and operation of a coupling-pin and provided at the front part of the lower opening with a ledge, of spaced apart forwardly extending projections on the front portion of the coupler-head, a knuckle pivoted between said projections and having an arm adapted to extend into and traverse the cavity of the coupler-head, the said arm having on its free end a vertical flange and at the lower portion of its free end a horizontal flange, means on the aforesaid projections and arm to restrict the rearward movement of the knuckle, a longitudinally slotted coup- 125

ling-pin movably located in the openings in the coupler-head and having at its upper end a head and near its lower end a shoulder adapted to rest on said ledge, the said pin 5 having at its lower end a reduced portion provided with a downwardly extending projection, a block having a shouldered mortise to receive and engage the reduced portion of the coupling-pin and projection thereon, re- 10 spectively, and pivotally and eccentrically secured to said reduced portion, a bell-crank-operating-lever fulcrumed between the walls of the housing and having one of its arms ex-

tended into the slot of the coupling-pin and another of its arms projected forwardly to 15 co-act in a lateral movement with the vertical flange on the arm of the knuckle, substantially as described.

In testimony whereof, I have signed my name to the specification in the presence of 20 two subscribing witnesses.

ALFRED CHURCHER, JR.
